UNITED STATES PATENT OFFICE.

ELMER G. LANTZ, OF TILLAMOOK, OREGON.

OIL-BURNER.

1,241,404.

Specification of Letters Patent. Patented Sept. 25, 1917.

Application filed December 29, 1916. Serial No. 139,602.

To all whom it may concern:

Be it known that I, ELMER G. LANTZ, a citizen of the United States, residing at Tillamook, in the county of Tillamook and 5 State of Oregon, have invented new and useful Improvements in Oil-Burners, of which the following is a specification.

The invention relates to burners, and more particularly to the class of oil burners.

10 The primary object of the invention is the provision of a burner of this character wherein the oil is vaporized prior to the consumption thereof by the flame, and the parts of the burner are materially simplified 15 so as to eliminate complication and difficulty in the cleaning thereof.

Another object of the invention is the provision of a burner of this character wherein there is arranged an adjustable flame 20 spreader or combustion pan which slides back and forth on the generating pipe of the burner, thereby controlling the fire or flame to permit keeping the generating pipe hot with a small fire and thus effecting a saving 25 of fuel consumption.

A further object of the invention is the provision of a burner of this character wherein the fuel nozzle is of a novel construction so that it can be readily cleaned 30 at the point of the aperture to avoid the choking or clogging thereof.

A still further object of the invention is the provision of a burner of this character which is extremely simple in construction, 35 thoroughly reliable and efficient in operation and inexpensive of manufacture and installation.

Other objects will be in part obvious and in part hereinafter pointed out.

40 The invention accordingly consists in the features of construction, combination of elements and arrangement of parts which will be exemplified in the construction herein-after set forth, and the scope of the application 45 of which will be indicated in the claims hereunto appended.

In the accompanying drawings:

Figure 1 is a side elevation of a burner constructed in accordance with the invention;

Fig. 2 is an end elevation thereof;

Fig. 3 is a top plan view.

Fig. 4 is a vertical longitudinal sectional view through the body;

55 Fig. 5 is a perspective view of the sliding flame spreader or combustion pan; and

Fig. 6 is a sectional view on the line 6—6 of Fig. 1.

Similar reference characters indicate corresponding parts throughout the several views of the drawings.

Referring to the drawings in detail, the burner comprises a generating pipe 10 which may be of any desired length and has connected thereto through the medium of a reducing nipple 11, at one end thereof, an oil supply pipe 12, while at the opposite end of the generating pipe is mounted a gooseneck shaped nozzle 13, having the straight portion 14 parallel with the generating pipe 10, and this straight portion 14 at its inner perforated end 15, is formed with a central aperture 16 through which is emitted the fuel for consumption, while adjustably threaded in the outer open end of the straight portion 14 is a bushing 17, through which works an adjusting stem 18 formed at its inner end with a cleaning head 19 provided with a pointed tip 20 which is adapted to enter the aperture 16 for removing any particles of dirt therefrom on the inward movement of the stem 18, the stem 18 being formed with external threads 21 to engage in companion threads 22 formed internally of the bushing 17, so that the head 19 can be locked with the bushing to hold the head retracted with respect to the perforated end 15 of the straight portion 14 of the nozzle. The outer end of the stem 18 carries a knurled disk 23 which permits the turning of the stem to unlock the same from the bushing 17 for permitting the inward movement of the same to force the head 19 in the direction of the perforated end 15 of the straight portion 14 of the nozzle, whereby the tip 20 will be inserted in the aperture 16 for the cleaning thereof. Surrounding the stem 18 without the nozzle is a coiled expansion spring 24 which serves to automatically move the cleaning head in an outward direction toward the bushing 17 so as to hold the said head and its tip away from the apertured end of the straight portion of the nozzle.

Movably supported upon the generating pipe 10 is a flame spreader or combustion pan which comprises a trough 25 formed with a reduced forward nose end 26 and also provided with upstanding ears 27 which are spaced from each other and are formed with openings 28 to accommodate the generating pipe 10, and in this manner the said

flame spreader or combustion pan is hung suspended from the said generating pipe. By reason of the mounting of the flame spreader or combustion pan upon the generating pipe 10 the flame from the fuel discharged through the nozzle 13 is permitted to play upon any portion of the generating pipe and when the spreader or pan is shifted close to the nozzle 13 it confines the flame 5 to a small space in the front of the stove, thereby keeping the generating pipe hot with a small fire and with resultant minimum consumption of fuel. However, by 10 sliding the spreader or pan away from the nozzle 13 the extent of the flame is increased upon the generating pipe, thereby increasing the heat within the stove to any point desired. Arranged within the oil supply pipe 12 is a cut-off valve 29 which controls 15 the supply of fuel or oil to the burner nozzle, as will be clearly apparent.

From the foregoing description, taken in connection with the accompanying drawings the construction and operation of the 25 invention will be readily apparent, and a more extended explanation, therefore, has been omitted.

Having thus described my invention, I claim:

- 30 1. A burner of the class described comprising a generating tube, a burner nozzle connected therewith and having an aperture, a tubular bushing threaded into the burner nozzle opposite said aperture, a valve rod 35 slidable through said bushing, a head on the valve rod, the bushing being internally threaded and the head being externally threaded for engagement with the interior threads of the bushing whereby the head is

locked against movement, a spring for retracting the head and means for rotating the valve rod to engage or disengage the head from the bushing. 40

2. A burner of the class described comprising a generating tube, a burner nozzle connected therewith and having a discharge aperture, a tubular bushing threaded into the burner opposite the discharge aperture, a valve rod slidable through the bushing, a head on the valve rod having a cleaning tip 45 adapted to be inserted in said aperture, spring means for retracting the head, the bushing being internally threaded and the head being exteriorly threaded and means for rotating the valve rod to lockingly engage the head with or to disengage the head from the internal threads of the bushing. 50

3. A burner of the class described, comprising a horizontal generating tube, a burner nozzle connected therewith having a discharge aperture with its axis substantially parallel with the generating tube, a trough like combustion pan, a pair of ears formed on the combustion pan and slidably 65 engaging the generating tube to support the combustion pan, the ear adjacent the nozzle being spaced from the bottom of the pan thus allowing passage of flame to the rear of the pan and the second ear serving to 70 close such end of the combustion pan.

In testimony whereof I affix my signature in presence of two witnesses.

ELMER G. LANTZ.
